PILLOW

Cornelia R. Nash, 291 Leicester, Detroit, Mich. 48202

Filed July 22, 1970, Ser. No. 24,067

Term of patent 14 years

Int. Cl. D6—09

U.S. Cl. D3—9

FIG. 1

FIG. 1 is a front perspective view of a pillow showing my new design.

FIG. 2 is a left side elevational view thereof on a reduced scale, and

FIG. 3 is a top plan view thereof on a reduced scale.

I claim:

The ornamental design for a pillow, substantially as shown.
